UNITED STATES PATENT OFFICE.

EUGENE M. BOURNONVILLE, OF JERSEY CITY, NEW JERSEY.

INTERNAL-COMBUSTION ENGINE.

1,229,574.

Specification of Letters Patent. Patented June 12, 1917.

Application filed September 23, 1915. Serial No. 52,155.

To all whom it may concern:

Be it known that I, EUGENE M. BOURNONVILLE, a citizen of the United States, and resident of Jersey City, in the county of Hudson and State of New Jersey, have invented certain new and useful Improvement Relating to Internal-Combustion Engines, of which the following is a specification.

10 The invention comprises certain improvements in rotary valves of multicylinder internal combustion engines, the same being more particularly designed for use in valves of the kind disclosed and claimed in my 15 Patent No. 1,118,730 of November 24, 1914, an alternative form whereof is shown and claimed specifically in my Patent No. 1,119,494, dated December 1, 1914. In these 20 patents a cylindrical valve member, conveniently termed "the valve," having means for controlling both intake and exhaust of each of the series of cylinders, rotates in the bore or cylindrical valve chamber of a suitable casing, which latter is provided also 25 with a longitudinal passage traversed by the gaseous fuel mixture on its way to the cylinders, the said passage being open substantially continuously to the surface of the valve, whereby the valve heated by the 30 exhaust is cooled and lubricated throughout its length by the current of fresh gases, containing, of course, vaporizable gasolene and also bearing an appropriate quantity of lubricating oil supplied in a suitable manner. 35 Cooling of the valve, in addition to that obtained by water-jacketing, is secured by causing the fresh fuel gases to flow through both a longitudinal passage in the interior of the valve and an intake manifold embodied in the casing, this manifold preferably 40 having a continuous or substantially continuous longitudinal opening into the valve seat bore, whereby the fuel current is conducted in contact with the surface of the valve throughout its length as aforesaid. 45 By these means the combined intake and exhaust valve, despite the high heat of the exhaust gases, is kept relatively cool and continuously supplied with lubricant, in order that the great defects of prior rotary 50 cylindrical exhaust valve structures, namely

seizing of the valve and cutting of the surfaces, due to overheating and failure of lubrication, may be avoided.

The present invention supplies another 55 feature of great importance to the preservation of the surfaces, namely the ability of the valve floating on its oil film to play or shift slightly in a longitudinal direction while rotating, so that any one point on the 60 valve, for example, a particle of carbon, is prevented from turning in the same place and therefore cannot cut a groove. The driving mechanism is separated from the valve and so constructed as to turn the same 65 without restraining its transverse or longitudinal play.

The valve is preferably made in two or more separated sections, with a driving member interposed between them and fixed 70 on an independent drive shaft extending within the interior of the valve, whereby the valve sections are driven simultaneously but with full freedom for play as indicated.

In one embodiment of the invention the 75 fuel gases are admitted to the internal passage of the rotating valve member intermediate its ends, preferably at the middle, and thence flow in both directions to enter the opposite ends of the intake manifold. In 80 this way all of the gases are compelled to flow through the interior of the valve, thereby securing the greatest cooling for this member, while at the same time uniformity of charges, as to temperature, quantity and 85 composition, are insured for all the cylinders. The central, driving member attached to the internal shaft may be laterally ported to afford inlets for the fresh gases; and in order to prevent the fuel mixture entering 90 directly into the manifold the inner cylindrical wall of the valve casing is carried across the open side of the manifold opposite the driving member. Opposite the valve sections, however, the opening is continuous 95 as in my prior patents.

These and other features of the invention will become apparent as the specification proceeds and will be more particularly pointed out in the claims.

In the accompanying drawings:
Figure 1 is a vertical longitudinal section

through the upper portion of a four cylinder engine embodying the present valve improvements.

Fig. 2 is a vertical cross-section on the line 2—2 of Fig. 1;

Fig. 3 is a cross-section on the line 3—3 of Fig. 1;

Fig. 4 is a central horizontal section through the valve and valve casing;

Fig. 5 is a section on the line 5—5 of Fig. 1;

Fig. 6 is a perspective view of a driving member which is interposed between sections of the valve;

Fig. 7 is a vertical longitudinal section through the valve casing of the embodiment of the invention shown in the preceding views;

Fig. 8 is a detail face view of a portion 20 of the valve showing one of the external pockets;

Fig. 9 is a vertical longitudinal section through another embodiment of the invention;

Fig. 10 is a central horizontal section through this form of the valve; and

Fig. 11 is an end view of the central driving member employed in this instance.

The engine cylinders, of which four are shown for purposes of illustration, are designated 1, and pistons therein are indicated at 3. Each cylinder has in its head a slot-like port 4, which serves alternately for intake and exhaust. The valve casing 6 is arranged lengthwise over the heads of the cylinders, with which it may be cast integrally if desired. The cylinder ports 4 open into the bottom of the bore of the casing, and on either hand are an intake manifold 11 and 40 exhaust openings or ports 10, the latter leading to a suitable exhaust manifold 33. In cases where the valve casing is cast with the cylinders its water-jacket 23 also constitutes an integral extension of the cylinder jackets. 45 In the body of the valve casing the valve seat bore and the intake manifold 11 extend lengthwise without interruption and are open at both ends, where they are closed to the atmosphere and placed in communication 50 with each other by two caps 50 and 51 having chambers 52 and 53.

The cylindrical valve 5 turning in the valve seat bore has a central bore or passage 7, to be traversed by the fuel mixture, and lateral, external pockets 8, to connect the cylinder ports alternately with intake and exhaust, as in my prior patents aforesaid. The valve is made in sections, in order to avoid warping and secure freedom 60 for independent play, it being desirable to provide a separate section for each cylinder, as set forth in my prior patents, though one section may be made to serve two cylinders as herein shown for purposes of illustration.

A central drive shaft 54 extends through the interior of the valve and is journaled in bearings 55 and 56 in the two caps 50 and 51, of which the bearing 55 at the driving end receives the greater part of the lateral thrust. 70 The shaft passes through this cap, the joint being made tight by a stuffing box 57, and outside of the same bears a sprocket wheel 17, by means of which the shaft and valve are driven by power derived from the crank-shaft. As a convenient means of adjusting the angular position of the valve with respect to the crank-shaft, the said sprocket wheel is itself loose on the shaft, but is adapted to be clamped against a shoulder 58, 80 thereon by a slideable cone-clutch member 59 backed by a nut 59a.

A driving member 60 or 60a is fixed on the drive shaft intermediate its ends and between the valve sections 5a and 5b, with the 85 ends of which it engages by means of interfitting tooth and recess formations 30 of known character, which permit longitudinal movement of the valve sections and are also sufficiently loose for a certain amount of lateral and angular movement. Longitudinal play of the valve sections in outward directions is limited by bearing of the outer ends of the sections with shoulders 61 on the caps 50 and 51, as clearly shown in Fig. 1, and the 90 relation between the lengths of the valve seat in the casing, included between these shoulders, of the valve sections and of the driving member 60 or 60a, is such that each of the valve sections shown has an end play of one-sixteenth of an inch. This clearance is substantially preserved under working conditions, because of the effective cooling provisions, with the result that the valve sections, floating on their oil film and unrestrained 95 either by the driving member or by each other, are free to shift endwise, back and forth to a slight degree, while in their rotation opening and closing the communications 100 between each cylinder and the intake and 105 exhaust.

A total lateral clearance, amounting to from about two to about four one-thousandths of an inch, is provided between the cylindrical surfaces of the valve and valve seat, which clearance is also not substantially altered during running, thereby allowing the valve sections to shift laterally, or up and down, slightly, throughout the length of each section, so as to enable the lubricant 110 carried by the fresh gases and deposited on the valve surface to work between all portions of the contacting and heated surfaces. This oil film is sufficient to prevent leakage around the valve and render special packing 115 provisions between the cylinders unnecessary.

In the embodiment of the invention shown in Figs. 1 to 7 the driving member 60 is relatively long, is hollow like the valve sections 120

proper, and has a skeleton wall, united to the shaft by a web 65, and affording large inlets 66 for the admission of fuel gases from a carbureter connection 67 communicating with a large port 68 in the side wall of the valve seat. At its ends it is provided with the teeth 30, which enter corresponding recesses in the ends of the valve sections, or obviously the teeth could be on the valve sections and the recesses in the driving member. 5 Just inside of these engaging formations the driving member is provided with endwise projecting flanges 75, which enter rabbeted recesses in the ends of the valve sections. 10 In this construction the fuel mixture which enters centrally of the valve divides and flows in opposite directions through the central bore 7 into the chambers 52 and 53, whence the two streams enter the opposite ends of the manifold 11. From the said manifold charges enter the cylinders in proper sequence when the cylinder ports 4 are connected with the manifold by the pockets 8. In this way all or substantially 15 all of the fresh gases are compelled to pass through the interior of the valve, the two streams flowing therethrough are never reversed in direction, and all reversals occur in the intake manifold, thus favoring the 20 deposition of the carried lubricant at the regions where it is to be utilized. The said lubricant is supplied to the current of fuel gases in the manner disclosed in my prior 25 patents, or by any suitable oil feed whereby 30 drops of oil are introduced into the gaseous stream and thereby atomized and carried along. One or more nozzles for delivering the oil may be provided at suitable points in the path of the fuel mixture, as represented, for example, at 38. 35

As in the said prior patents, the intake manifold communicates with the face of the valve by means of a substantially continuous longitudinal opening or passage 70 in 40 the valve seat wall. In the particular construction shown in Figs. 1 to 7, the manifold is blanked off from the ports in the central driving member 60 by means of a wall portion 69, which extends on either 45 side slightly beyond the outer part of the driving member and prevents the fuel mixture passing directly to the manifold from the carbureter connection without passing lengthwise through the valve. With the 50 exception of this region, however, the opening or openings 70 in the wall of the valve seat are uninterrupted and the presence of the wall 69 is of no moment as far as lubrication is concerned, because in practice the 55 driving member is made with a clearance between it and the wall of the casing of about ten one-thousandths of an inch, which is substantially larger than the clearance allowed for the valve sections and practically precludes touching. In addition the 60 inner wall of the valve casing where it surrounds the driving member is largely cut away to form the large inlet port 68, and by way of this port and the large openings in the side of the driving member more than 70 sufficient lubricant reaches these particular surfaces. It may be noted that the distance from the inner ends of the nearest cylinder ports 4 to the inner ends of the valve sections 5^a and 5^b is about one inch in practice, which is enough to enable the oil film to prevent gases being forced into the space around the driving member and thence back into the carbureter on the compression and firing strokes. A small amount of the fresh 75 gases find their way out through the joints between the driving member and the valve sections and enter the intake manifold, but this is really an advantage because it insures lubrication around the extreme ends of the 80 valve sections. 85

The flanges 75 projecting within the valve sections hold the parts in relative position, without interfering with the play of the valve sections, their particular function being to keep the driving member 60 or 60^a from touching the wall of the casing bore, which would be liable to occur owing to the 90 flexibility necessarily present in the drive shaft. The clearance between the external 95 surfaces of the flanges and the internal surfaces of the valve sections with which they coöperate should accordingly be less than the clearance allowed between the outside of the driving member and the wall of the 100 casing bore. The inner ends of the valve sections, in fact, constitute a species of center bearing for the drive shaft, and the lateral support or confinement thus afforded is sufficient to make it permissible to dispense with the bearing 56 in the cap 51, or 105 in other words to omit the rear half of the shaft entirely. It will be understood, however, that such bearing does not hold the parts against play, and that both the valve 110 sections and the driving member may vibrate up and down freely, and that the longitudinal play of the valve sections is in nowise interfered with. From the foregoing it will be perceived that the drive 115 shaft 54, owing to the considerable distance between the bearing 55 and the driving member 60 or 60^a, constitutes in effect a flexible driving connection, which, under my conditions, avoids the valve sections being 120 held against play transversely to their length. 125

The construction illustrated in Figs. 9 to 11 differs from that of Figs. 1 to 7 in that the carbureter connection is at one end instead of intermediate the ends of the valve. To this end the cap 51^a is provided with a conduit 67^a leading from the carbureter. As in the form first described, the effective 130 cross-sectional areas of the bore 7 and of the

1 manifold 11 are each approximately half the area of one of the cylinder ports 4. Consequently the gaseous stream is compelled to divide, approximately one-half flowing 5 through the interior of the valve to the far chamber 52, the other half entering directly into the manifold. In this embodiment the driving member 60^a may be made much shorter than in the first construction, and, 10 since it has no openings in its sides, the wall section 69 of the other figures is unnecessary, so that there is a single continuous opening 70 from end to end of the compound valve. In both instances the lower edges of these 15 openings, that is to say, the edges nearer the cylinder ports are substantially straight, while the portions of the upper edges corresponding in position to the pockets 8 are curved upward as shown, so that the widest 20 parts of the opening or openings are in the same transverse planes as the centers of the pockets, measured lengthwise. Between the pocket-bearing lengths of the valve, the upper edges of the said openings are brought 25 closer to the lower edges. In this way the cooling and lubricating currents have the greatest access to the valve surface at zones central with respect to the length of the pockets, where the heat is greatest, and at 30 the same time the area of cylindrical surfaces at these regions is reduced. It will be understood, of course, that the upper edges of the openings 70 may be inclined upward, rather than curved, to high points opposite 35 the middle of the pockets, without affecting the result.

A further detail relates to the formation 40 of the pockets 8 by which the intake and exhaust gases are passed to and from the cylinders. These pockets instead of having their end walls 72 meeting the bottom at an angle are curved inward, toward each other, and merge into the bottom as shown in the various longitudinal sections and in Fig. 8. This 45 has the desirable effect of directing the exhaust gases emerging from the cylinder ports away from the end corners 73 of the exhaust ports 10 in the valve casing, thereby saving these edges from burning. The sides 50 74 of the pockets are also preferably curved in the same manner, in order to afford a stream-line path for the gases, but this is not as important as the incurving of the end walls.

55 While I have described two embodiments of the present improvements in detail, it is to be understood that I do not limit myself to the precise constructions shown and that other equivalent embodiments of part or all 60 of the improvements may be devised by those skilled in the art.

What I claim as new is:

1. In an internal combustion engine, comprising a series of cylinders, a casing having 65 a cylindrical valve seat bore extending

lengthwise of said series, a rigid cylindrical rotary valve floating on an oil film in said bore with freedom for unforced longitudinal play under working conditions, and means for driving the valve while permitting play 70 thereto.

2. In an internal combustion engine, comprising a series of cylinders, a casing extending lengthwise of said series, being formed with a cylindrical valve seat bore, a rotary valve comprising separate rigid cylindrical sections, each having means for controlling the intake and exhaust of one or more cylinders, each of said valve sections floating in said bore with freedom for independent unforced longitudinal play, and an independent coaxial drive shaft having means for turning the valve sections and permitting their play. 75

3. In an internal combustion engine, comprising a series of cylinders, a valve casing extending lengthwise of the series and formed with a cylindrical valve seat bore, a hollow rotary valve comprising separate rigid cylindrical sections turning in said bore, a central independent drive shaft, and a member on said drive shaft between the ends of two valve sections formed to drive said sections simultaneously while permitting independent longitudinal and transverse play thereof, the valve sections being 90 free to move in either longitudinal direction. 95

4. In an internal combustion engine, comprising a series of cylinders, a valve casing extending longitudinally of said series and 100 formed with a cylindrical valve seat bore, a hollow rotary valve therein comprising separate rigid cylindrical sections, and an independent driving shaft within the valve having means at the middle thereof for simultaneously driving the sections on either hand with freedom for relative play, the valve sections being free to move in either longitudinal direction. 105

5. In a multicylinder internal combustion engine, a valve casing extending longitudinally of the series of cylinders and formed with a cylindrical valve seat bore, rigid cylindrical rotary valve sections in said bore, and driving means disposed between the sections for driving the same independently of each other, the said valve sections being free to play longitudinally in the valve seat bore relatively to the driving means during the operation of the engine. 110 115

6. In an internal combustion engine, a rigid rotary hollow cylindrical valve and a flexible driving connection passing within the interior of the valve permitting free play to the same in its seat in all transverse directions. 120 125

7. In a multicylinder internal combustion engine, the combination of a valve casing extending longitudinally of the series of cylinders and formed with a cylindrical valve 130

seat bore, a plurality of rigid cylindrical rotary valve sections free to float in said bore under working conditions, and separate driving means with which the valve sections are independently engaged.

5. In a multicylinder internal combustion engine, the combination of a valve casing extending longitudinally of the series of cylinders and formed with a cylindrical valve seat bore, a plurality of hollow rigid cylindrical rotary valve sections, a central drive shaft, and means on said shaft between the valve sections and separate therefrom for driving the same, the valve sections being free to float in the bore of the casing.
10. In a multicylinder internal combustion engine, the combination with a valve casing having a valve seat bore, and an intake manifold opening into the side of said bore, of a valve turning in the bore and comprising separate sections having means for connecting the intake manifold with the engine cylinders at the proper times, said valve sections being further provided with longitudinal internal passages for conducting the fresh gases to the intake manifold, means of communication between said internal valve passages and the manifold, a driver between proximate ends of the valve sections, said driver being hollow and laterally open for admission of the fresh gases to the longitudinal passages in the valve sections, and an inlet for fresh gases opposite the driver.

15. In an internal combustion engine, comprising a series of cylinders, a valve casing extending longitudinally of the series and having an intake manifold and exhaust openings, a hollow rotary valve in said casing comprising sections adapted to connect the cylinders alternately with said intake manifold and exhaust openings, a central independently journaled drive shaft, a hollow member carried by said drive shaft between adjacent valve section ends and having engagement therewith whereby the valve sections are permitted to have independent relative play, said member having open sides, and means for supplying thereto fresh fuel gas mixture, which passes longitudinally through the interior of the valve sections in opposite directions and thence at the ends into said intake manifold.

20. In an internal combustion engine, comprising a series of cylinders, a valve casing extending lengthwise of said series and formed with a valve seat bore, exhaust openings therefrom, a longitudinal intake manifold, and a substantially continuous longitudinal opening in the wall of said bore connecting the latter and the intake manifold, a rotary valve in said casing having a longitudinal internal passage and external pockets in its walls adapted to connect the cylinders alternately with said intake manifold and exhaust openings, means of com-

munication between both ends of the passage in the valve and the ends of the intake manifold, and means for admitting the fresh fuel gas mixture to the said valve passage intermediate the ends thereof.

25. In an internal combustion engine comprising a series of cylinders, a valve casing extending lengthwise of said series and formed with a valve seat bore, exhaust openings therefrom, a longitudinal intake manifold, and a substantially continuous longitudinal opening in the wall of said bore connecting the latter and the intake manifold, a rotary valve in said casing having a longitudinal internal passage and external pockets in its walls adapted to connect the cylinders alternately with said intake manifold and exhaust openings, means of communication between both ends of the passage in the valve and the ends of the intake manifold, said valve having an entrance for fresh gases intermediate its ends, a carburetor connection terminating in a port opening through the wall of the casing at this region, and means for preventing said fresh gases passing directly across into the intake manifold.

30. In an internal combustion engine comprising a series of cylinders, a valve casing containing an intake manifold, a rotary valve in the casing having a hollow interior communicating at both ends with said intake manifold, and means for supplying fresh fuel gas mixture to the interior of the valve intermediate its ends to flow in opposite directions into said intake manifold, the manifold being continuous from end to end.

35. In an internal combustion engine, comprising a series of cylinders, a valve casing extending longitudinally of said series and formed with a valve seat bore, cylinder ports, exhaust openings, an intake manifold, and an intake opening or openings from said manifold into the valve seat bore, and a rotary valve in said bore having pockets for connecting the cylinders alternately with the said intake and exhaust openings, the intake opening or openings having their edges farther from the cylinder ports curved or cut-in so that the said openings are widest opposite the central portions of said pockets.

40. In an internal combustion engine, comprising a series of cylinders, a valve casing extending longitudinally of said series and formed with a valve seat bore, cylinder ports, exhaust openings, an intake manifold, and an intake opening or openings from said manifold into the valve seat bore, and a rotary valve in said bore having pockets for connecting the cylinders alternately with the said intake and exhaust openings, the intake opening or openings having their edges nearer the cylinder ports
